UNITED STATES PATENT OFFICE

155,098

DESIGN FOR A TABLE LAMP

Carl McClellan, Detroit, Mich.

Application December 13, 1948, Serial No. 150,120

Term of patent 7 years

(Cl. D48—20)

To all whom it may concern:

Be it known that I, Carl McClellan, a citizen of the United States, residing at Detroit, Michigan, have invented a new, original, and ornamental Design for Table Lamps, of which the following is a specification, reference being had to the accompanying drawing, forming part thereof, wherein:

Fig. 1 is a side elevational view of a table lamp showing my new design.

Fig. 2 is a top plan view thereof, the dotted lines showing a lamp socket being omitted.

The dominant characteristics of my design reside in the portions shown by means of full lines in the drawing.

I claim:

The ornamental design for a table lamp, as shown and described.

CARL McCLELLAN.
